UNITED STATES PATENT OFFICE.

JACOB TOPOR, OF CHICAGO, ILLINOIS, ASSIGNOR TO HANDY FURNITURE MANUFACTURING COMPANY, OF CHICAGO, ILLINOIS, A CORPORATION.

TABLE.

1,385,762.

Specification of Letters Patent. Patented July 26, 1921.

Application filed February 11, 1920. Serial No. 357,824.

To all whom it may concern:

Be it known that I, JACOB TOPOR, a citizen of Poland, residing at Chicago, in the county of Cook and State of Illinois, have invented 5 certain new and useful Improvements in Tables, of which the following is a specification.

This invention relates to certain new and useful improvements in Tables, and the primary object of the invention is to provide 10 a table with a plurality of compartments or drawers which are revolvably mounted beneath the table top so that any desired one of the drawers may be brought to any 15 desired point for opening of the same, and placing of articles therein or taking the same therefrom.

A further object of the invention is to 20 provide a table of the above character wherein the revolvably mounted drawers are so related to the table top as to not interfere with the use of the latter at any time or to detract from the appearance of the table.

A still further object of the invention is 25 to produce a table of the above type which is of extremely simple and durable construction and capable of being easily and cheaply manufactured.

With these general objects in view and 30 others that will appear as the nature of the invention is better understood, the same consists in the novel construction, combination and arrangement of parts hereinafter more fully described, illustrated in the accompanying drawings, and then claimed.

In the drawings forming a part of this application and in which like designating characters refer to corresponding parts throughout the several views,

40 Figure 1 is an elevational view, partly in vertical central section, of a table constructed in accordance with the present invention,

Fig. 2 is a top plan view of substantially one-half thereof, the table top being indicated by dotted lines to clearly illustrate details of the revolving frame which carries the drawers, and parts being broken away to show further details,

Fig. 3 is a horizontal sectional view taken 50 substantially upon line III—III of Fig. 1,

Fig. 4 is a fragmentary view partly in elevation and partly in vertical section and showing the relationship of the drawer-carrying frame and its supporting platform,

55 Fig. 5 is a fragmentary perspective view

of the supporting platform for the drawer-carrying-frame,

Fig. 6 is a view similar to Fig. 5 of the drawing-carrying frame, and

Fig. 7 is a perspective view of one of the 60 drawers.

Referring to the drawings more in detail, the present invention comprises a table or like article of furniture embodying a supporting standard or pedestal 5, having the 65 usual legs 6, which may be of any desired character and design. The standard 5 is reduced at its upper end to provide a cylindrical portion 7 and a shoulder 8 at the base of said cylindrical portion, a platform 70 9 of any preferred form in plan, preferably circular, being disposed on the cylindrical portion 7, so as to rest upon the shoulder 8 and the braces 10 which are rigidly carried by the standard 5.

The table top 11 is preferably of the same 75 form as the platform 9 although slightly greater in diameter, and is provided with a central squared socket in its under surface as at 12, for snugly receiving the reduced extreme end portion 13 of the standard 5. Suitable posts 14 are disposed vertically at intervals between the platform 9 and top 11 so as to rigidly connect the latter, to hold the same 80 against relative movement, and to maintain 85 their spaced relation as seen in Fig. 1. These posts are preferably provided with dowel pins 15 at their opposite ends fitting and rigidly secured within sockets of similar form provided in the platform 9 and top 11. 90

A skeleton frame is rotatably mounted between the platform 9 and the top 11, and the same includes a hub 16, provided with radial rigid drawer guides or spokes 17, arranged in vertical pairs and connected 95 rigidly by carrier partitions or boards 18 which are also radially arranged. It is noted that the partitions 18 outwardly diverge, and a post 14 is positioned in front of the extreme outer end edge of each of 100 said partitions 18, the space between each pair of posts 14, allowing for the unobstructed movement of the drawers 19 inwardly and outwardly for the opening and closing thereof. To provide a more durable 105 and practical construction, each upper and lower pair of guides 17 is connected by a horizontal board 19 being rigidly fastened to the outer ends of adjacent spokes in any well known or preferred manner. In order 110

to reduce friction as far as possible, I mount a plurality of anti-friction rollers or the like as at 20 at suitable intervals in the upper surface of the platform 9 so that the lower boards 19 rest thereon in such manner that when the drawer-supporting frame is rotated, said anti-friction devices will revolve and provide little resistance to the rotation of said frame. It is of course understood that the hub 16 is revolvably mounted on the standard portion 7 so that the drawer-supporting frame is spaced a slight distance from the adjacent surfaces of the platform 9 and top 11. By disposing the partitions 18 and guides 17 radially, it becomes necessary to utilize a drawer of peculiar shape in plan as shown in Fig. 7. This drawer comprises a vertical narrow rear end wall 21 and a relatively wide front wall 22 connected by outwardly diverging side walls 23 so as to inclose a substantially triangular space, a bottom 24 being provided for each drawer as is usual.

As shown in Fig. 1, the hub 16 may be connected with the radial guides 17 by suitable dowel pins 25, and an upstanding frame 26 may be placed upon the margin of the platform 9 in front of the forward edges of the boards 19 which connect the lower pairs of guides 17.

From the foregoing description it is readily seen that a person may assume a position at any point radially of the table, and withdraw a drawer at that point, or may revolve the drawer-supporting frame so as to bring any desired drawer within reach for the opening thereof. It will also be seen that I have provided an extremely durable and practical construction which has obvious advantages.

Minor changes may be made in the form, combination and arrangement of parts without departing from the spirit and scope of the invention as claimed.

Having thus described my invention, what I claim as new and desire to secure by Letters Patent, is:—

1. A table comprising a supporting pedestal having supporting legs and provided with a rigid reduced cylindrical upper end portion providing a shoulder at the base of said reduced portion, a circular horizontal platform fitted upon said cylindrical portion and resting on said shoulder, a circular horizontal table top non-rotatably fitted

upon the upper end of said pedestal in spaced relation to and above said platform, a horizontal frame revolvably mounted upon the cylindrical portion of the pedestal between the table top and the platform and including inwardly converging drawer guides and radially movable substantially triangular sliding drawers carried by said frame. 60

2. A table comprising a supporting pedestal having supporting legs and provided with a rigid reduced cylindrical upper end portion providing a shoulder at the base of said reduced portion, a circular horizontal platform fitted upon said cylindrical portion and resting on said shoulder, a circular horizontal table top non-rotatably fitted upon the upper end of said pedestal in spaced relation to and above said platform, a horizontal frame revolvably mounted upon the cylindrical portion of the pedestal between the 70 table top and the platform and including inwardly converging drawer guides and radially movable substantially triangular sliding drawers carried by said frame, and means rigidly connecting the platform and 80 table top providing for the unobstructed outward movement of any of the doors of said frame at any point radially of the table. 75

3. A table comprising a supporting pedestal having supporting legs and provided with a rigid reduced cylindrical upper end portion providing a shoulder at the base of said reduced portion, a circular horizontal platform fitted upon said cylindrical portion and resting on said shoulder, a circular horizontal table top non-rotatably fitted upon the upper end of said pedestal in spaced relation to and above said platform, a horizontal frame revolvably mounted upon the cylindrical portion of the pedestal between the table top and the platform and including inwardly converging drawer guides and radially movable substantially triangular sliding drawers carried by said frame, and means rigidly connecting the platform and 90 table top providing for the unobstructed outward movement of any of the doors of said frame at any point radially of the table. 95

In testimony whereof I affix my signature.

JACOB TOPOR.
